(57) **CLAIM**

The ornamental design for a tire, as shown and described.

DESCRIPTION

FIG. 1 is a perspective view of a tire showing my new design;
FIG. 2 is a front view thereof, the rear view being a mirror image thereof;

FIG. 3 is a top plan view thereof, the bottom plan view being a mirror image thereof;

FIG. 4 is a left side view thereof;

FIG. 5 is a right side view thereof;

FIG. 6 is an enlarged sectional view of the intersection of areas 6—6 and 6'—6' in FIG. 2;

FIG. 7 is a cross-sectional view taken along line 7,8—7,8 in FIG. 5 and 7'—7' in FIG. 6; and,

FIG. 8 is a cross-sectional view taken along line 7,8—7,8 in FIG. 5 and 8'—8' in FIG. 6.

In the drawings, the broken lines defining the sidewall, inner bead and the peripheral boundary between the claimed tire tread and the unclaimed sidewall depict environmental subject matter that forms no part of the claimed design.
